CLAIM

The ornamental design for a tortilla toaster, as shown and described.

DESCRIPTION

FIG. 1 is a front perspective view of a tortilla toaster showing my new design;

FIG. 2 is a right side elevation view thereof;

FIG. 3 is a front elevation view thereof;

FIG. 4 is a left side elevation view thereof;

FIG. 5 is a rear elevation view thereof;

FIG. 6 is a top plan view thereof;

FIG. 7 is a bottom plan view thereof;

FIG. 8 is a front perspective view thereof in a dispensing mode; and,

FIG. 9 is a front perspective view thereof in a toasting mode. The broken lines shown in the drawings illustrate portions of the tortilla toaster that form no part of the claimed design. The tortilla toaster is shown with a symbolic break in its width indicated by the dash dot dot dash lines. The appearance of any portion of the article between the symbolic break lines forms no part of the claimed design.
